Specification for Design.

Patented Feb. 7, 1922.

Application filed July 28, 1921. Serial No. 488,244. Term of patent 3½ years.

To all whom it may concern:

Be it known that I, FREDERICK VINCENT WINTERS, a citizen of the United States, residing at New York, in the county and State of New York, have invented a new, original, and ornamental Design for a Tire Tread, of which the following is a specification, reference being had to the accompanying drawing, forming part thereof, in which—

Figure 1 is a plan view of a section of the tread.

Figure 2 is a cross section thereof taken on the line II—II of Figure 1, and

Figure 3 is a cross section thereof taken on the line III—III of Figure 1.

I claim:

The ornamental design for a tire tread, as shown.

FREDERICK VINCENT WINTERS.
